2 SHEETS—SHEET 2.

UNITED STATES PATENT OFFICE.

CLARK J. SMITH, OF OTTUMWA, IOWA, ASSIGNOR TO THE HARDSCOG WONDER DRILL CO., INCORPORATED, OF OTTUMWA, IOWA.

WIRE-WORKING IMPLEMENT.

No. 927,691.

Specification of Letters Patent.

Patented July 13, 1909.

Application filed October 27, 1908. Serial No. 459,738.

To all whom it may concern:

Be it known that I, CLARK J. SMITH, residing at Ottumwa, in the county of Wapello and State of Iowa, have invented certain new and useful Improvements in Wire-Working Implements, of which the following is a specification.

My invention relates to certain new and useful improvements in implements for cutting, forming and applying wire fastenings to hose pipe couplings and my invention has for its object to provide a simple and effectively constructed implement whereby a fastener wire may be bent into shape while a second wire is applied to the coupling and a third wire is being cut.

The invention also has for its object to provide an implement wherein the fastener wire may be cut, bent and applied by one and the same implement without the use of auxiliary tools.

More specifically the invention embodies those novel details of construction, combination and arrangement of parts all of which will be first described in detail and then be specifically pointed out in the appended claims, reference being had to the accompanying drawings, in which—

Figure 1 is a perspective view showing how my invention may be used to simultaneously apply a wire to the coupling, form another wire and cut a third wire. Fig. 2 is a central, vertical, longitudinal section of the coupling, the parts being shown in one position. Fig. 3 is a similar view, the parts being in another position. Fig. 4 is a top plan view of my invention. Fig. 5 is a vertical longitudinal section on the line 5—5 of Fig. 4. Figs. 6 and 7 are cross sections on the line 6—6 of Fig. 4, looking in the direction of the arrows *x* and *y* respectively. Fig. 8 is a rear elevation of my implement. Fig. 9 is a detail perspective view of the main frame. Fig. 10 is a similar view of the sliding carriage. Fig. 11 is a detail perspective view of the wire clamping end of the carriage.

Referring now to the accompanying drawings in which like letters and numerals of reference indicate like parts in all of the figures, 1 designates the main frame which is provided with a T-shaped channel formed by the bottom 1^b, sides 1^a and the bent over top edges 1^c. At the front of the frame 1 the sides 1^a are provided with lining depressions 1^d that are curved as at 1^e to form cam surfaces and

the depressions 1^d merge with depressions 1^f in the opposing faces of the bent over ends 1^c, as clearly shown in Fig. 9 of the drawings. The bottom 1^b near the front end is provided with perforations 1^g which register with perforations 2^g in the sliding carriage 2 to form a cutting mechanism. At the rear the main frame 1 is provided with a back plate 1^k which carries an anvil 1^m that has a groove 1ⁿ for a purpose hereinafter more clearly understood and the back plate 1^k is provided with longitudinal alining apertures 1^p through which the ends of the wire *w* may be passed.

The carriage 2 is provided on its upper 70 face with rack teeth 2^a, the front ones of which are cut away, as at 2^d, to leave a space between the rack teeth 2^a and the adjacent edges of the bent over ends 1^c of the main frame 1, the space being slightly more than 75 the thickness of the wire *w*. The front rack member 2^b is provided with slightly beveled portions 2^c to receive the wire *w* when it is bent into form to prevent it slipping off the member 2^b. At the rear the carriage 2 has 80 grooves 2^f and a bearing lug 2^e to which a cam grip lever 3 is pivoted at 3^a, the lever 3 having serrated cam surfaces 3^b to enter the grooves 2^f. The grooves 2^f, it should be understood, aline with the apertures 1^p in 85 the back plate 1^k of the frame 1 so that when the wires are projected through the apertures 1^p they will project into the grooves 2^f and may be gripped by the cam lever as shown in Fig. 2 of the drawings. 90

The main frame 1 has ears 1^h through which the pivoted ends 4^a of the lever 4 pass, the lever 4 being provided with a segment 4^b to mesh with the rack teeth 2^a so that as the lever 4 is manipulated to turn the segment 4^b on its axis the carriage 2 will be reciprocated in the frame 1. 95

In the practical application of my invention the wire is cut into approximately the desired lengths, and it is then placed in the 100 depressions 1^d of the main frame 1, it being understood that the carriage 2 is drawn to its backmost position. The lever 4 is then moved in the direction of the arrow in Fig. 2, causing the carriage to be forwardly directed, thus bringing the front rack tooth 2^b into engagement with the wire and thereby by carrying it along and causing it to be bent into a U-shape. The wire rests in the depressions 1^f, as it is formed, while the cam 110

surfaces 1^e serve to raise the ends of the wire clear of the frame 1, as it is being bent into the U-shape, so that the wire will lie adjacent to the teeth 2^a in the cut-away portions 5 2^d thereof. Upon moving the lever 4 in an opposite direction to turn the carriage 2 to its backward position, the formed wire will be released. In forming the wire the two legs of the U are not always of the same length 10 so it becomes necessary to trim them off or they may be longer than is desired, and may need trimming off for that reason. In order to trim the wire to the proper length after it is formed into the U-shape, the ends are 15 passed through the apertures 1^g in the bottom 1^b of the main frame 1 and through the apertures 2^g of the carriage 2, it being understood that the apertures 2^g and 1^g are first brought into alinement. As soon as 20 the wire has been projected through such apertures 1^g and 2^g, the desired distance, the lever 4 is brought down to project the carriage forwardly, causing the wire ends to be cut or broken. After the wire has been 25 formed into U-shape, it is bent around the hose coupling in the usual manner with the ends projected through the loops and the ends of the wire are then passed through the apertures 1^P and clamped by the clamp 3, 30 after which the lever 4 is brought down to move the carriage forward. This brings the portion w' of the wire into the saddle 1ⁿ and as the carriage moves forwardly the wire will be tightly drawn around the coupling. 35 As soon as the wire has been drawn taut the coupling is rolled around the anvil 1^m until the wire is bent to hold it from slipping. After which, the wire is released from the clamp 3, withdrawn and bent down by using 40 the implement as a hammer in any desired manner. A wire may be bent into a U-shape while a second wire is being cut and a third wire is being applied to the hose coupling, by one and the same movement of the 45 lever 4, as indicated in Figs. 1, 2 and 3 of the drawings.

From the foregoing description, taken in connection with the accompanying drawings, it is thought the complete construction, operation and advantages of my invention will be readily understood by those skilled in the art to which the invention appertains.

What I claim is:

55 1. A wire working implement comprising a main frame and a carriage slidable therein, and means for reciprocating said carriage, together with means forming a part of the main frame and carriage for cutting, forming and applying a wire to a hose coupling.

60 2. A wire working implement comprising a main frame and a carriage reciprocal therein, and means for reciprocating said carriage, of means forming a part of the frame and carriage for bending a wire into

U-shape, said carriage and said frame having means for simultaneously trimming the ends of a preformed wire.

3. A wire working implement comprising a main frame and a carriage reciprocal therein, and means for reciprocating said carriage, of means forming a part of the frame and carriage for bending a wire into U-shape, said main frame and said carriage having provisions for cutting a second wire to size while 70 the first wire is being formed.

4. A wire working implement comprising a main frame and a carriage reciprocal therein, and means for reciprocating said carriage, of means forming a part of the frame and carriage for bending a wire into U-shape, said main frame and said carriage having provisions for cutting a second wire while 80 the first wire is being formed and said carriage and main frame also having provisions 85 for simultaneously applying a third wire to a hose coupling.

5. A wire working implement, comprising a main frame and a carriage reciprocal therein, and means for reciprocating the carriage, 90 said main frame having notches to hold a wire across the path of travel of the carriage, means mounted on said carriage to engage said wire as the carriage is reciprocated and bend the same, and means forming a part of 95 the frame for directing the wire out of the notches as it is bent into form.

6. A wire working implement comprising a main frame and a sliding carriage mounted therein, and means for reciprocating the carriage, said main frame having depressed portions to receive a wire, the said carriage having an abutment to engage said wire, said depressions of the main frame having cam surfaces so that as the carriage is moved in 100 one direction the wire will be bent into a U-shape, substantially as shown and described.

7. A wire working implement comprising a main frame and a reciprocating carriage 110 mounted therein, and means for reciprocating said carriage, said main frame having a bottom and sides and bent over top edges to form a T-shaped passageway for the sliding carriage, said sliding carriage having a rack portion, one of the rack teeth of said rack portion having depressions, the sides and bent-over top edges of the main frame having cut-away portions to coöperate with the depressed portions of the rack teeth of the 115 carriage so that a wire when placed across the carriage in the cut-away portions of the main frame may be engaged by the depressed portion of the rack tooth of the carriage and bent into U-shape.

8. A wire working implement comprising a main frame consisting of a bottom and sides terminating in upper bent-over edges spaced apart to leave a passageway, said sides and upper bent-over edges having cut- 130

away portions provided with cam faces, the adjacent edges of the bent-over portions having supplemental depressions merging with said cut-away portions, a sliding carriage mounted in said main frame and having provisions for coöperating with said cut-away and depressed portions of the main frame for bending a wire into a U-shape as the carriage is reciprocated.
